UNITED STATES PATENT OFFICE.

WILLIAM F. NICHOLS, OF CHICAGO, ILLINOIS.

GLOBE-GUARD SUPPORT.

1,267,444.

Specification of Letters Patent. Patented May 28, 1918.

Application filed March 6, 1917. Serial No. 152,866.

To all whom it may concern:

Be it known that I, WILLIAM F. NICHOLS, a citizen of the United States, residing at Chicago, Cook county, State of Illinois, have 5 invented certain new and useful Improvements in Globe-Guard Supports, of which the following, taken in connection with the drawings, is a description.

My invention has for its object the production of a globe guard support, designed 10 to be used in connection with arc light globes, about which is placed a wire guard or protector such as is now in common use. Heretofore it has been customary to attach 15 the wire guard to rings suspended from or attached to the globe support, which necessitated the removal of the same every time it became necessary to take the globe out, all of which required time and expensive labor. 20 One of the objects of my invention is to provide a guard support which is placed inside of the rim of the globe and remains there and is removed with the globe whenever it becomes necessary to remove it, thus 25 doing away with the detailed work of removing the wire guard before the globe can be removed.

A further object of my invention is to produce a device of this class which may be 30 used in connection with globes held in position either by springs or screws of the kind now on the market, so that the guard may be attached to any size of globe without alteration with respect to the fixtures accompanying it.

A further object of the invention is to provide a support of this kind which will retain the parts in their proper position even if the globe should be cracked or broken, as 40 is sometimes the case.

A further object of my invention is to provide a support which may be placed in position in the globe and be practically invisible from the outside, and one which is so constructed 45 that it will allow for the contraction and expansion of the globe with the heat and cold.

Other objects of advantage in the construction and use will be apparent to those skilled in the art to which it pertains.

In the accompanying drawings, I have illustrated what I now consider the preferred form of my invention, although the details thereof may be varied as to size, proportion, etc., without departing from the spirit thereof, and in these drawings,

Figure 1 is a side elevation of the upper portion of an arc light globe with my apparatus attached thereto;

Fig. 2 is a transverse sectional detail, 60 taken on line 2-2 of Fig. 1;

Fig. 3 is a plan view of a section of a strip of material out of which my guard is made;

Fig. 4 is a fragmentary detail, illustrating 65 the manner of joining the ends of the guard when brought together to form a ring or circle;

Fig. 5 is a fragmentary detail of the ring or circle, illustrating the manner of attaching one of the guard-retaining hooks, and 70

Fig. 6 is an enlarged sectional detail through the ring and one of the hooks.

In carrying out my invention, A represents an arc lamp globe, which is of the construction now in general use, having a neck or rim *a* formed on the top thereof. My guard support is designed to fit inside of 75 this rim *a* and is provided with a flange which rests upon the top thereof. 80

This support is formed preferably of a thin sheet of metal B, a section of which is shown in Fig. 3, which is bent, folded and overlapped on the lines *b*, *b'*, *b*², into the form of construction shown in Fig. 6, one 85 edge of the material, *a'*, being folded inside to give the device strength and rigidity, the opposite edge, *a*², extending at right angles to the last fold and forming an outwardly extending circumferential flange, which is 90 of the same diameter as the rim *a* of the globe which it is to fit.

Before the elongated strip of material B is bent and overlapped as previously explained, the hooks C, which are also formed 95 of the same kind of thin sheet metal, are cut to the desired shape and placed at the different points desired on the guard and folded with the material in the form shown in Fig. 6.

The inner end *c* of each hook is folded inside of the inner fold *a'* of the ring, as shown in Fig. 6, and projects beneath the outer edge of flange *a*² of the ring, where it is bent into the curve *c'*, to which the wires 105 *c*² forming the guard are secured.

When the blank C forming the hook is placed in position on the material B forming the ring and bent with it as shown in Fig. 6, the metal is tapped to press the parts 110 together, as shown at *d*. This means of securing the parts together is very quickly and

effectively done in assembling the parts, in effect riveting them together; without providing a fastening which would be affected by the heat, as would solder or the like.

5 The ends of the material B after being bent in the lengthwise folds preparatory to forming the ring, are brought together as shown in Fig. 4, and secured in the same manner previously described, the hook C in
10 this instance having a wider base, d, which is folded inside of the rim and secured by the indentations, d', upon each side thereof.

In the drawings I have shown the guard provided with four hooks for engaging the wires forming the guard, but it is obvious that more or less of these hooks may be provided, depending upon the size of the globe upon which it is to be used, the guards being made in different sizes to accommodate any
15 20 of the different sizes of globes as now made.

I claim:

1. A globe guard support, comprising a ring formed of a single piece of material, one longitudinal edge thereof being bent, 25 folded and overlapped upon itself leaving the opposite edge to form an outwardly extending circumferential flange adapted to rest upon the rim of the globe, and means projecting from said ring and engaging the
30 guard, substantially as described.

2. A globe guard support, comprising a

ring formed of a single piece of material, one longitudinal edge of which is bent, folded and overlapped upon itself, the ends of said piece of material being joined together to form a ring having an outwardly extending circumferential flange, and a plurality of engaging devices having one end of each folded inside of the ring and secured therein, substantially as described. 35

3. A globe guard support comprising a ring formed of a single piece of material, one longitudinal edge of which is bent, folded and overlapped upon itself, the ends of said piece of material being joined together to form the ring having an outwardly extending circumferential flange, a plurality of engaging devices secured in said ring at predetermined distances apart and extending outwardly therefrom to engage the guard, 40 substantially as described.

4. A globe guard support, comprising a ring formed of a single piece of material having the ends thereof joined together, engaging hooks projecting from the periphery 45 of said ring and engaging the guard, said hooks being secured to the ring by indentations through the metal forming the same, substantially as described.

In testimony whereof I have signed this 60 specification.

WILLIAM F. NICHOLS.
